UNITED STATES PATENT OFFICE.

EDWARD D. DOUGHERTY, OF BELLEVUE, PENNSYLVANIA.

DESIGN FOR A METALLIC FASTENING-WASHER.

SPECIFICATION forming part of Design No. 32,218, dated February 13, 1900.

Application filed December 19, 1899. Serial No. 740,943. Term of patent 14 years.

To all whom it may concern:

Be it known that I, EDWARD D. DOUGHERTY, a citizen of the United States of America, residing at Bellevue, in the county of Allegheny and State of Pennsylvania, have invented a certain new and useful Design for a Metallic Fastening-Washer, of which the following is a specification, reference being had therein to the accompanying drawings.

My invention relates to a certain new and novel design for metallic fastening-washers, and has for its object to provide a design for a washer of new and original shape.

As shown in the accompanying drawings, the washer consists of the novel outline and configuration, which will be hereinafter more fully described and specifically pointed out.

In describing the invention in detail reference is had to the accompanying drawings, forming a part of this specification, and wherein like numerals of reference indicate like parts throughout both views, in which—

Figure 1 is a perspective view of my new and original design for metallic fastening-washers. Fig. 2 is a cross-sectional view thereof.

Referring to the drawings by reference-num-

erals, 1' indicates a concentric disk having a circular opening 1' and provided with a series of slits an equal distance apart, forming 30 thereby a series of integral sections 2 of the outer portion of the disk. The one corner 3 of each of the integral sections is curved downwardly, forming a pointed barb, while each of the sections at the opposite end from the 35 curved corner are bent upwardly toward the axial line of the disk in a curvilinear manner, as at 4, which forms the edge of each section in a curvilinear manner from end to end, as at 5, the curve extending downwardly from 40 the top of the bent portion 4 to the opposite corner thereof.

Having fully described my invention, what I claim as new, and desire to secure by Letters Patent, is—

The design for a metallic fastening-washer, substantially as shown and described.

In testimony whereof I affix my signature in the presence of two witnesses.

EDWARD D. DOUGHERTY.
